UNITED STATES PATENT OFFICE.

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

FUSE-PLUG.

1,385,285.

Specification of Letters Patent. Patented July 19, 1921.

Application filed March 23, 1920. Serial No. 368,062.

To all whom it may concern:

Be it known that I, GEORGE B. THOMAS, a citizen of the United States of America, residing at Bridgeport, in the county of Fairfield and State of Connecticut, have invented 5 certain new and useful Improvements in Fuse-Plugs, of which the following is a specification.

My invention relates to fuse plugs, and 10 particularly to the electrical connection between the fuse and the center and shell contacts of the plug. The object of my invention is to provide simple and efficient terminals for a fuse of the type shown in the 15 Goodridge Patent No. 1,330,630, dated February 10, 1920.

In the accompanying drawings—

Figure 1 is a side elevation of a fuse plug in which my invention is embodied in one 20 form, the screw shell side contact of the plug and the plug cap being omitted;

Fig. 2 is a vertical section on the line 2—2, Fig. 1, showing the screw shell and cap in position;

Fig. 3 is a plan of the plug with the cap removed;

Fig. 4 is a perspective of the fuse and the associated spring terminal;

Fig. 5 is a vertical section corresponding 30 to Fig. 2 but showing a modified construction of the spring terminal;

Fig. 6 is a perspective of the fuse and spring terminal shown in Fig. 5;

Fig. 7 is a partial vertical section through 35 a plug showing a further modification of the spring terminal and having associated therewith a fuse wire; and

Fig. 8 is a perspective of the spring terminal shown in Fig. 7, together with the fuse 40 wire.

In the construction illustrated in the Goodridge patent above referred to, the connection between the fuse and the center and shell contacts of the plug is effected by direct mechanical engagement, thus eliminating 45 the use of solder. While the construction there shown is perfectly satisfactory from an electrical standpoint, it involves certain manufacturing difficulties which are 50 remedied by my present invention.

Referring to Figs. 1 to 4, the present plug comprises the usual insulating body 10, having a fuse chamber 11 from which opens the well 12 formed between the barrier 13 and

the upper portion of the fuse body. The 55 usual cap 14 closes the chamber, the interior of which is visible through the mica insulating disks 15. The entering end of the plug body is externally threaded at 16 to receive the screw shell 17 side contact, which forms 60 the side wall of the lower portion of the well 12. At the nose of the plug a center contact disk 18 is secured by means of a rivet 19, the large head 20 of which overlies the lower perforated end 21 of the fuse strip 65 22, and thus forms a closure for the hole through which the rivet passes.

The opposite end 23 of the fuse strip is carried over the barrier 13 and down toward the bottom of the well 12. To establish 70 electrical connection between this end of the fuse strip and the screw shell 17, I provide a spring terminal 24 having a base 25 adapted to enter the well and bear against the inserted end 23 of the fuse. A lug 26 struck 75 outward from the base 25 engages the shoulder 27 at the top of the well, and prevents the terminal from slipping upward in the well. The spring end 24 of the terminal normally extends outward beyond the area 80 defined by the shell 17, so that when the latter is screwed on the threads 16 of the plug body the spring tongue 24 is compressed and thus establishes good electrical contact with the screw shell, while at the 85 same time forcing the base 25 of the terminal into intimate contact with the end 23 of the fuse.

This construction has the merit of affording 90 sufficient range of adaptability to compensate for all practical variations in the diameter of the plug body, or in the screw shell, incident to the manufacture of these parts.

In Figs. 5 and 6 I have shown a modified 95 form of the spring terminal. In addition to the spring tongue 24, which is angled from one end of the base 25 of the terminal, I have provided a second spring tongue 28 at the opposite end of the base and having 100 an offset flange 29 which corresponds in function to the lug 26 of the construction shown in Figs. 1 to 4. This modification facilitates the assembly of the parts, since, upon insertion of the terminal, the spring 105 tongue 28 is compressed in the upper portion of the well between the barrier 13 and the body of the plug 10 and serves to retain

the terminal in position until the screw shell 17 is adjusted in position. The operation of assembling the spring terminal and fuse in the well 12 may therefore be carried 5 out at one place in the shop without danger of disarrangement of the spring contact before the screw shell 17 is adjusted at another part of the shop.

In Figs. 7 and 8 I have shown still another 10 modification of the spring terminal. In this form the base 25 is of sufficient length to extend substantially the full depth of the well, so that when the bend which forms the 15 spring tongue 24 is bottomed in the well, the opposite end of the base is still slightly above the top of the barrier 13, and in the assembled plug is engaged by the cap 14, or the 20 insulating mica disks 15. This construction enables the operator to force the spring terminal down into the well 12 from the top of the latter in the direction of the arrow X, Fig. 7. While facilitating the insertion of the terminal in this manner, the method is not desirable where the neck 30 of the well 25 is so narrow that the compression of the spring, incidental to its insertion, is sufficient to injure the spring bend, and thus to lessen the subsequent engagement between the 30 terminal and the screw shell.

Of course this construction is available if desired, whatever type of fuse is used. I have shown, however, in these figures a wire fuse instead of a fuse strip, as in the other figures, and I have, moreover, indicated the 35 wire as of sufficient length to be not only carried down to the bottom of the well, but also angled up at 31 between the spring terminal 24 and the screw shell 17, so that the fuse end is pressed by the latter directly 40 against the screw shell.

The direct electrical connection thus established between the fuse and the screw shell is practically desirable for fuses of higher capacity—say 30 ampere fuses.

When using a wire fuse the center contact 45 end thereof is curled into an eye 32, through which the center contact rivet 19 passes. A notch 33 may be formed in the spring bend to accurately locate the fuse wire end with 50 relation to the springs.

Various modified forms of terminals will readily occur to those dealing with the prob-

lem, which do not depart from what I claim as my invention.

I claim—

1. A fuse plug comprising an insulating body having a fuse chamber and a well opening therefrom to the exterior of the body, a screw shell side contact closing the exterior opening of said well, a fuse extending into said well, and spring means for effecting the electrical connection between said fuse and screw shell. 55 60

2. A fuse plug comprising an insulating body having a fuse chamber and a well opening therefrom to the exterior of the body, a screw shell side contact closing the exterior opening of said well, a fuse extending into said well and a spring arranged in 65 said well and having an outwardly extending tongue adapted to effect electrical connection between said fuse and the screw shell. 70

3. A fuse plug comprising an insulating body having a fuse chamber and a well opening therefrom to the exterior of the body, a screw shell side contact closing the exterior opening of said well, a fuse extending into said well and spring means for effecting the electrical connection between 75 80 said fuse and screw shell, together with means for maintaining said spring in predetermined position in said well.

4. A fuse plug comprising an insulating body having a fuse chamber and a well opening therefrom to the exterior of the body, a screw shell side contact closing the exterior opening of said well, a fuse extending into said well and spring means for effecting the electrical connection between 85 90 said fuse and screw shell, together with spring means for maintaining said terminals in predetermined position in the well.

5. A fuse plug comprising an insulating body having a fuse chamber and a well opening therefrom to the exterior of the body, a screw shell side contact forming a side wall of said well, a fuse extending into said well, and spring means for pressing said fuse against the screw shell to establish direct 95 100 electrical contact between said parts.

In testimony whereof I have signed my name to this specification.

GEORGE B. THOMAS.
